D. D. GRANGER.
RUBBER HEEL.
APPLICATION FILED FEB. 4, 1919.

1,314,393.

Patented Aug. 26, 1919.

UNITED STATES PATENT OFFICE.

DANUS D. GRANGER, OF NEW LONDON, OHIO.

RUBBER HEEL.

1,314,393.

Specification of Letters Patent. Patented Aug. 26, 1919.

Application filed February 4, 1919. Serial No. 274,894.

To all whom it may concern:

Be it known that I, DANUS D. GRANGER, a citizen of the United States, residing at New London, in the county of Huron and State of Ohio, have invented a new and Improved Rubber Heel, of which the following is a specification.

My invention has for its object to provide an improved rubber heel of a simple and inexpensive construction and whose upper and lower faces are especially designed to co-operate for effecting a more positive tendency of the heel to adhere to the shoe and the lower or tread face to effect a sure grip, when brought into engagement with the ground, while walking.

My invention also has for its purpose to provide a rubber heel having upper and lower suction surfaces that coact in such manner, whereby to produce opposite pulling actions on the said two faces, as the lower or tread face tends to more firmly adhere to the ground, when lifting the foot and increase suction action created on the upper face that causes the said upper face to the more effectively adhere to the shoe to which it is attached.

Again my invention embodies, in a rubber heel of the general character stated, an improved means for permanently attaching the said heel to the shoe with a less number of nails and in a more effective manner than has heretofore been done in that type of rubber heels which include an independent washer in connection with the head of each fastening nail.

With other objects in view that will hereinafter appear, my invention embodies, in a rubber heel, the peculiar features of construction and novel combination of parts as will be stated in the following detailed description, specifically pointed out in the appended claims and illustrated in the accompanying drawings, in which:

Figure 1 is an inverted plan view of a rubber heel constructed in accordance with my invention.

Fig. 2 is a longitudinal section thereof taken on the line 2—2 on Fig. 1.

Fig. 3 is a top plan view of my said improved rubber heel.

Fig. 4 is a cross section thereof on the line 4—4 on Fig. 3.

Fig. 5 is a top plan view of a modified construction of my improved rubber heel.

Fig. 6 is a cross section thereof on the line 6—6 on Fig. 5.

In carrying out my invention, the heel body is of the conventional external contour and is formed of that grade of rubber of which rubber heels are usually composed.

In my construction of heel and in the preferred form thereof, the upper and lower faces of the heel are each provided with suction surfaces or elements that work together, that is the suction action imparted to the lower face 1 as the foot is lifted during walking, increases the suction at the upper face 2 in the manner presently more fully explained.

In my improved form of rubber heel, the bottom or lower face has suction elements that consist of a series of ring-like concavities 3 that surround a center concavity 4.

The several ring-like concavities 3 are separated, at the tread surface, by flat tread portions whose peripheral edges terminate in undercut portions 6 instead of straight edges, the reason for which is explained as follows:

By making the said edges or portions 6 undercut or projected at an acute angle inwardly relatively to the tread face of the heel, as is best shown in Figs. 2, 3 and 4, it follows that as the heel wears down, the said ring-like tread surfaces 5 substantially maintain their original narrow width and the suction concavities their full width, such arrangement of parts providing, as it were, an increased life of the suction elements on the tread and thereby maintain, for a long time during the use of the heel, the full effect of the said suction elements.

7 designates a reinforce tread portion at the extreme rear end of the heel whose face is in a plane somewhat below the tread face that has the suction elements, it being understood that the said portion 7 serves the usual function of preventing a too rapid wearing down of the rear extremity of the heel.

As before stated, both the upper and lower faces of the heel have suction surfaces or elements that co-operate, as will be now explained.

The upper face 2 of the heel has a central concavity 20 whose outer edges 8 taper and merge with a bearing surface 9 that extends entirely around the concavity 20 and which terminates in substantially straight edges 10.

that constitute one wall of a surrounding channel or groove 11, whose other wall merges with an outer flat bearing surface 12 which extends entirely around the sides, 5 front and rear portions of the heel, as is best shown in Fig. 3.

By forming the upper face of the shoe, as shown and described, the central concavity 20 and the outer channel 11 act as suction elements 10 which aid in holding the heel to the shoe sole, when it is attached thereto by nailing in the usual manner, it being apparent that when walking, as the suction elements on the bottom of the heel cause the heel to 15 grip or adhere to the ground, such pulling action as is applied at the bottom of the heel tends to pull the heel away from the shoe and, in doing so, it increases the action of the suction elements 20 and 11 and thereby 20 causes the heel to hold tighter to the shoe.

In my construction of heel, instead of providing a separate washer for coöperating with each nail head, as is usually the case in the formation of rubber heels, a flat plate 25 13 is embedded in the heel body and the said plate has a series of apertures 14 that align apertures 15—15 which extend through the heel and through which fastening nails (not shown) are passed, when securing the heel 30 to the shoe.

By using a single plate, as stated, simplifies and cheapens the means for securing the heel to the shoe, since the one plate acts as a washer for all of the nails and provides 35 for attaching the heel with a less number of nails than is necessary when using a separate washer for each nail.

Figs. 5 and 6 illustrate a modified construction of my improved heel. In this 40 form, instead of providing the upper face of the heel with suction elements, the said face is constructed for cushioning the heel and for such purpose, the said upper face is provided with an annular depression or 45 channel 16 that surrounds a central annular bearing surface 17, which, in turn, surrounds a central concavity 18 that connects with the outer channel 16, by one or more passages 22—22.

50 The outer channel 16 communicates with one or more air passages 23—23 that open through the back of the heel, as shown.

When formed with a cushioning means at

the top, as stated, the heel may be made of a more solid rubber than is necessary when 55 the top portion has suction elements, since the cushioning features provide the desired elasticity or spring that is lost by reason of using a heavier or more solid rubber than that which is necessary, when the top face 60 is provided with suction elements, as in Figs. 1, 2, 3 and 4, it being understood that when using the modified form of heel, Figs. 5 and 6, the air is pumped into the channels 16 and 18, when lifting the heel off the ground 65 and expelled during the treading action.

From the foregoing description taken in connection with the drawings, the complete construction and the advantages of my improved rubber heel will be readily apparent 70 and need not be further referred to.

What I claim is:

1. A rubber heel having a tread portion 75 provided with suction elements that consist of a series of annular concavities and a ring-like tread portion between each pair of concavities, the outer peripheral walls of the said ring-like portions being undercut or inclined inwardly.

2. A rubber heel having a tread portion 80 provided with suction elements that consist of a series of annular concavities and a ring-like tread portion between each pair of concavities, the outer peripheral walls of the said ring-like portions being undercut and inclined inwardly, the upper parts of the extremities of the concavities over-lying the undercut edges of the ring-like tread portions.

3. A rubber heel having a lower or tread 90 portion provided with suction elements that consist of a series of annular concavities and a ring-like tread portion between each pair of concavities, the outer peripheral walls of the said ring-like tread portions being undercut or inclined inwardly, said heel having an upper face provided with a central suction concavity and a suction groove or channel surrounding the central concavity and located near the outer edge of the heel. 95

4. A rubber heel having an upper face provided with a central suction concavity and a suction groove or channel surrounding the central concavity and located near the outer edge of the heel.

DANUS D. GRANGER.
